ELECTRICAL CALCULATING EQUIPMENT

William Hatton and Ladislas Kozma, Antwerp,
Belgium, assignors to International Standard
Electric Corporation, New York, N. Y.

Application April 5, 1940, Serial No. 328,150
In Great Britain April 4, 1939

12 Claims. (Cl. 235—61)

This invention relates to electric systems, such as those for the control of a plurality of calculating machines.

An object of the invention is to provide for the working of equipments to be checked during slack periods, and this without the necessity of substantially increasing the number of equipments in the system.

In accordance with this invention an electric system provided with a plurality of similar equipments is characterised in that, when the number of equipments in use is less than a certain value, further equipments are brought into use in pairs, which work in parallelism so as to check their working, but when the number of equipments in use is more than said value, further equipments are brought into use singly.

In accordance with a further feature of the invention an electrical system provided with a plurality of similar equipments is characterised in that the equipments are brought into use in pairs, which work in parallelism so as to check their working, but that when all the equipments are in use a further call upon the system is satisfied by the release of one equipment from a pair already in use.

By similar equipments is meant those that, although not necessarily of identical construction and operation, will, in response to identical signals or inputs, give identical results or outputs.

In order that the invention may be clearly understood reference will now be made to the accompanying drawings in which:

Figs. 1, 2, 2A and 3, show in detail the use of the invention in connection with a bank of calculating machines all accessible from a number of operator's stations; and

Fig. 4 is a key diagram for Figs. 1, 2, 2A and 3.

In connection with the system to be described, it is assumed that a large house, such as a bank or department store, is equipped with a plurality of calculating machines located at one point, and makes all these centrally located machines severally available to a larger number of operators scattered throughout the building. Each calculating machine includes a line-finder to which every operator's set is banked. When a call comes in from an operator, the line finders of all those calculating machines that are idle at that time begin to function, and the first to find the calling line puts its calculating machine into communication with that operator's set so that it can take the job. The advantage of such

a system in respect of economy in the number of calculating machines to be provided is obvious.

The present invention is concerned with giving to an operator who calls during a time when the calculating machines are slack, the benefit of a check upon the work of the machine that may be allotted to him for that job, by pairing off two machines at random from among those that are idle, so that the pair of identical machines, working in parallel, will give notice to the operator if their two results contradict one another. If the traffic increases and reaches a certain value, the checking for all further calls is suppressed. Further, if, when a new call enters, no calculating machine is available, the system provides for one of the machines in a pair to be released to take up the new job. The number of already existing pairs to be severed may simply be equivalent to the increase in the demands being made upon the system; on the other hand the pairing may be completely broken down throughout the entire system.

In Figs. 1 to 3 of the drawings, which are intended to be read as a whole being placed as indicated in Fig. 4, Fig. 1 shows an individual operator's set OS and the line circuit LC; Figs. 2 and 2A illustrate so much of two calculating machines I and X as is necessary for an understanding of the invention, and in particular show the line finders and associated selector portions of such calculators; while Fig. 3 shows the pairing suppressing circuit PS.

When an operator has thrown the starting key SK and has been connected through to the calculating machines, one machine during busy times and two during slack, he manipulates the various operating keys OK each representing in code a certain numerical value between 0 and 9 or a certain function such as "add" or "subtract," and thus sends in the problem to the allotted calculator(s) over the lines A.

After the necessary calculations have been made the answer is returned over the lines B to some suitable indicator such as a printer P. The present invention may be applied to any type of calculating machine which is operable by electric signals over two or more wires such as A, and which also transmits its results as electric signals over two or more wires such as B. The preferred type of calculator is one which is capable of performing all four basic calculations: addition, subtraction, multiplication, and division, one such calculator being described in British Patents 525,330 and 525,396 both published August 27, 1940, as well as in the U. S.

patent application of Ladislas Kozma and Jacob Kruithof filed Nov. 9, 1939, Serial No. 303,504, and being further described in Belgian Patent No. 437,386.

The present application discloses an arrangement for attaching one or two calculators to a single operator's sender. The invention is concerned solely with that feature of the organization as a whole. The details of the calculator are not herein disclosed, since they have nothing to do with the invention per se, as here claimed. Only so much is shown of each calculator as is necessary to understand how they are connected with the system both for receiving and sending back impulses to the controlling circuits.

One main feature of the present invention is that, instead of providing separate reserve calculators or special routine test equipment, for the purpose of testing the calculator taken into use, one of the regular calculators is paired with the calculator first taken into use, when and only when such second calculator is free and not in use, so as to duplicate all calculations and thus to indicate whether or not the calculator taken into use functions correctly, or effectively so. Each operation is thus simultaneously performed twice and if the two operations correspond precisely to one another, one obtains an effective indication of the correctness of the operation. The chances of two of the regular calculators being subject to the same fault at the same time are negligible.

Operation with paired checking

To originate a call, the operator at one of the operator's sets OS has to throw the starting key SK. While there has been shown only a single operator's set, it is to be understood that there can be a very large number of such sets, all connected to a multiple extending along the line finders of a plurality of calculators, as elsewhere explained in detail.

Common start relay FS (Fig. 3) operates from battery through 200 ohm resistor R1 (Fig. 1), right contacts of SK, 800 ohm resistor R2, and common start wire W1 (Figs. 1, 2, 3). FS in turn operates ST which is provided with separate front contacts for each selector circuit by which latter expression is meant the circuit which, through the operation of a line finder, will cause the selection of a particular calculator or calculators for the use of a given operator's set, e. g. the set shown in Fig. 1 (only three sets of such contacts being shown). The operation of ST energizes the clutch magnets LFM associated with the line finders LF of all idle calculators, e. g. of calculator I in Fig. 2 and of calculator X in Fig. 2A, each via the back contacts of its associated T1 and T2 relays and the respective front contacts of ST. Thus the line finders LF of all the calculating machines that are at that moment idle start to rotate. Line finders employed in this organization may be of any suitable type as well known in the automatic telephone art, for example, such line finders as are disclosed in U. S. Patent No. 1,882,981, issued to Scheiber et al. Test potential is connected via the 200 ohm resistor, R1 and left hand contacts of SK to wire w1 which extends the corresponding j terminal, i. e. the third j terminal (which is the only one shown in Figs. 2 and 2A) of every free line finder LF. The connections from every operator's set are multiplied over all the line finders in the usual way, so that the ten wires, wa3 . . . wh3, w13, w23, which are individual to operator's

set number 3 are connected in each finder to ten of the terminals of the third row. Only the third row of terminals is shown in Figs. 2, 2A.

The operator's sending set is connected with the multiple banks of the finder switches in the same manner in which a telephone subscriber's station is connected with the terminal banks of line finders in automatic telephone exchange systems. As shown in Figs. 1, 2 and 2A, all the wires leading to an operator's sending set are multiplied to corresponding sets of terminals in a plurality of line finder banks. Assuming that the set of terminals shown in Figs. 2 and 2A are the first set that the line finder wipers engage during their rotation, the second set of terminals of the two line finders illustrated will be multiplied to a second operator's sending set. Since each operator's sending set must be accessible to more than two calculators, the sending set will be multiplied not only to the terminal banks of two line finders, but to the terminal banks of many additional line finders, preferably to all the line finders in the system.

Suppose that the first among the line finders to reach its third position and thus pick up the calling potential on its contact j is that forming part of the calculating machine I (Fig. 2); relay T1 in this machine will operate from such test potential on this j terminal, brush j of LF, high resistance left hand winding of T1 to ground, and will stop the driving magnet LFM by opening its above traced circuit which passes through the back contacts of T1.

The operation of T1 also initiates what is generally known as a "double test." More particularly the closure of the front contacts of T1 grounds the 1½ ohm winding of D1 which is in series with the 3 ohm right hand winding of T1, so that this series combination (having a total resistance of 4½ ohms) is now connected to the lead from brush j and thence to test wire w13 in parallel with the high resistance left winding of T1. Since the battery potential on wire w13 is coming through 200 ohm resistor R1, the low resistance load now connected thereto drops the potential of this test wire w13 to a small fraction of its previous value so that any other T1 relays which may have their high resistance windings connected thereto in the next instant will be unable to operate. Even if by chance another T1 relay became connected to start wire w13 at the very same instant as that of calculator I and also cut in its low resistance winding exactly simultaneously, no accidental double connection will result. For the combined current of two 4½ ohm loads will reduce the voltage so low that neither T1 relay can hold even with their low resistance windings. Thus in such case both will release and then both will reoperate, repeating this action until one gets ahead of the other and connects in its own low resistance winding at an instant when the other has only its high resistance winding connected. The 1½ ohm D1 relays require even more current than the 3 ohm windings of the T1 relays. Thus if a repeated operation and release of two T1 relays occurs the associated D1 relays will not be operated during such chattering operation.

When finally one of the T1 relays (say that of calculator I) operates and stays operated three results are thereby accomplished. First the reduction in the potential of test wire w13 busies this test wire with respect to the selector circuits of all other calculators, i. e. prevents the test relay T1 of any other calculator from sub-

sequently operating, as above explained. Second this reduction of potential of w_{j3} also reduces the energization of common start relay FS since the voltage for FS comes also from the same resistor R1 to which w_{j3} is connected. FS however will probably not actually release at this time because it almost immediately receives a fresh energization as described below. Third the operation of T1 causes operation of D1 in series with the low resistance winding of T1.

The operation of D1 operates relay Q over left outer front contacts of D1. Also it connects test potential via 200 ohm resistor RB, right hand back contacts of F, right hand inner front contacts of D1, to wire w_{k3} , which is multiplied to the third k terminals of all line finders LF. At the same time it applies this same potential via RB, right back contacts of F, right outer front contacts of D1, 800 ohm resistor RA to common start wire W1, thus giving start relay FS the fresh energization above mentioned. Hence the line finders LF of all the other still available calculating machines continue to rotate until one of them finds the k test potential. Suppose that it is the line finder of machine X which does this, then its relay T2 operates from this test potential, brush k of LF, high resistance left hand winding of T2, to ground and stops its driving magnet LFM by opening its above traced circuit at the back contact of T2. After successful "double testing," in the same manner previously described for the T1 relay in the circuit of calculator I, relay D2 in this machine operates like relay D1 in the calculator I. Simultaneously the starting relay FS is shunted out again, but this time it releases, since no fresh potential is connected to re-energise it. The release of FS releases ST which opens the circuits of clutch magnets LFM of all other line finders, so that now the other still rotating line finders stop, if, of course, no other call is originated at the same time.

Relay D2 in machine X operates the ready-to-take relay RT not only in the machine X but also in the machine I. In calculator X (Fig. 2A) the circuit extends directly from ground, via right make contacts of D2, to relay RT of calculator X. For the RT relay of calculator I the circuit extends from ground, via the right make contacts of D2 (Fig. 2A), right contacts of Q, brush l of LF, thence over wire w_{i3} to brush l of LF (Fig. 2), right contacts of Q to relay RT (Fig. 2). RT applies ground over its outer right front contacts to wire SCW which places the calculation circuits in condition to receive codes, if these circuits are of a type requiring this. As well known in the art, calculators of this type are frequently arranged to send back to the operator an "attachment" signal, in order that the operator may know when a calculator has been properly connected to his sender, thus indicating to him that he may now begin to depress his various sending keys. Such attachment signals are usually in the nature of a few impulses, e. g. three dots, which signals will be sent out by a sending calculator, if only one such calculator has been connected to the sender OS of Fig. 1, but will be sent out jointly by the first and second calculators, in case that a pair of calculators is attached to the single sender OS. These attachment signals will be transmitted to the sender over the conductors W_{e3} , W_{f3} , W_{g3} , W_{h3} and W_{m3} . Such attachment signals do not constitute an essential portion of the present invention and the manner in which they are produced

by the calculator is accordingly thought not to be pertinent. The manner in which the signals operate printer P of Fig. 1 will be hereinafter described in greater detail. The operator of sender OS will be unaware of the connection or disconnection of a second calculator, since the attachment signals will be received, whether one or both calculators of a pair have been connected to his sender.

- 10 On receiving this indication the operator at the set OS manipulates the operating keys OK to send in his calculation problem over the four lines A. The code signals are received simultaneously by both calculating machines I and X over the brushes a, b, c and d, leading to the input relays A1 . . . A4, which are now connected in parallel in the two machines, over wires w_{a3} , w_{b3} , w_{c3} , w_{d3} .
- 15 The solution of the problem comes back to the apparatus P in the operator's set OS over the lines B, which include the relays B1 to B4, and the brushes e, f, g and h. If there should be a discrepancy between the solutions given by the two calculating machines, then one of the relays C1 to C4 in one of the units will operate. For example if the two relays B1 in calculators I and X did not agree in position, that in I being operated while that in X was not operated, relay C1 in calculator X would be energized from battery through front contacts of B1 (Fig. 2) fifth set of contacts from left in Q relay (Fig. 2), brush e of LF (Fig. 2), wire w_{e3} , brush e of LF (Fig. 2A), fifth contact from left of Q relay (Fig. 2A), back contacts of B1 (Fig. 2A), to winding of C1 (Fig. 2A). Such operation of C1 in machine X grounds wire w_{i3} over front contacts of C1, second set of contacts from right in Q relay (Fig. 2A), and brush i of LF (Fig. 2A).
- 20 Similarly, any other of the relays C1—C4 in either machine would, if operated, ground the wire w_{i3} . Any such ground on w_{i3} will operate the error relays E in both calculators (over brush i of LF and second contacts from right in Q relay of each calculator).
- 25 40 The E relay is connected in any suitable manner to prevent the printing in OS of the disagreeing signals now stored in relays B1—B4. The particular connection illustrated is suitable if the printer P in operator's set OS is of the general class whose character selection is prepared by energisation of a number of magnets (e. g. S1, S2, etc.) but whose printing is not effected until a print magnet P1 becomes energized over contact of one or more such magnets, S1, etc. The mechanism by which the type wheel is positioned under the control of the five selector magnets may be of any of the types well known in printing telegraphy. U. S. Patent No. 2,127,145 to R. D. Salmon, discloses one such mechanism in which the type wheel is positioned under the control of five crank pins 22 each of which can take up one of two positions diametrically opposed with respect to a common axis. Although each pin 22 in the disclosure cited is controlled by a revolvable disc, it will be clear to one skilled in the art that it could equally be controlled by an electro-magnet having an armature with an operated and an unoperated position. Another known method of positioning a type wheel under the control of five electro-magnets having two position armatures consists in driving the type wheel through a rack and pinion mechanism and system of levers, so disposed that upon the operation of one electro-magnet the rack is driven through a distance corresponding to one-half of
- 30 35 45 50 55 60 65 70 75

a revolution of the type wheel, whereas, upon the operation of a second, third, fourth and fifth electro-magnet the rack is driven through a distance corresponding respectively to $\frac{1}{4}$, $\frac{1}{8}$, $\frac{1}{16}$ and $\frac{1}{32}$ part of a revolution.

The printer is equipped with mechanical delay means whereby the printer magnet P_1 is prevented from energizing and causing the printing of a character while the type wheel is in motion, i. e. until the desired character has been selected.

It will be noted that the energizing circuit of magnet P_1 includes a front contact of one of the selector magnets S_1 to S_4 as well as the back contacts and armatures of the E relays. It is necessary, therefore, that one of the selector magnets be energized and that the E relay be in the normal or de-energized condition. If the E relay is energized, indicating the improper operation of a calculator, the printer magnet cannot become energized. Assuming the printer P is of such type as above described, then relay E disables the printing by removing battery from wire $wm3$ so that print magnet P_1 cannot operate.

For other types of printers the method of disabling printing would be modified.

The E relay also closes at its right front contacts a circuit which releases the calculator or blocks it in any known manner, e. g. by having its right hand armature and contact so connected as to blow the main fuse of the power supply feeding the calculator, so that all the printing operations determined by transmissions from this calculator will then cease, this stoppage of the printer thus serving to notify the operator who is manipulating sender OS , that the calculators to which his sender has been assigned, are not functioning properly.

The restricting relay RS (Fig. 3) operates when a new call comes in at a time when a certain predetermined number of calculating machines are in use, that is when a certain number of relays RT are operated. Each operated RT relay applies battery over RD via its outer left front contacts to point J (Fig. 3). This point is also connected to ground through resistor RE via ST left middle front contact each time ST is operated by a new call. Thus if four RT relays are operated, then when ST is operated by a new call, the four RD resistors in parallel will form one arm of a voltage divider of which RE forms the second arm, the point J thus having a potential dependent on the number of RT relays operated. RS is connected between point J and a fixed potential point K between resistors QR and OR . A rectifier RC is included in series with RS so that RS can only operate if J is more negative than K in potential. The value of the opposing resistance OR can be chosen so that the current will flow in the sense of the rectifier RC , when 60-70% of the calculators other than I are already occupied. The arrangement just described can be considered in the light of a Wheatstone bridge. Looked at from another viewpoint, it can be considered to be a Wheatstone bridge so balanced that the current which can flow over a single RD resistor (Figs. 2 and 2A), will be unable to establish any current flow through the rectifier RC , in the direction in which this rectifier is capable of transmitting current. The function of the particular unit comprising resistors RE , OR , QR and the rectifier RC as well as the battery connected to resistance OR , is to establish a certain stable potential across rectifier RC , so that current cannot flow therethrough

until the balance of the bridge is upset by changes in the external arm thereof, which arm comprises (connected in parallel) as many of the resistors RD , each one pertaining to an individual calculator,

5 as may happen by the operation of the RT relays of such calculators, to be placed in this external arm. If now this external arm has its resistance lowered by the placing therein of an RD resistance in addition to those already forming such arm, the balance of the voltage divider or Wheatstone bridge is upset, thus allowing current to flow through rectifier RC in such manner as to bring about the functioning of relay RS . While the conditions for establishing a Wheatstone bridge according to this description will be apparent to those skilled in the art, it may briefly be stated that if the resistance of RE be taken equal to the resistance of QR , and if the resistance of OR be made equal to the resistance presented by the external arm of the bridge, when 10 60 to 70 per cent of the total RD resistors are provided by the total calculators of the system, then the balance of the bridge will be such that relay RS will receive no current, except when more than 60 to 70 per cent of the calculators 15 become occupied by various senders. If RS is operated, it operates RZ which has a set of contacts connected separately to each calculator, and connects ground to the wires connected to the 20 back contacts of all the RT relays in the calculators, with the result that when a single line 25 finder finds the calling line involved in the new call, the operation of relay D_1 will bring about the following sequence of operations.

When the relay D_1 becomes energized, it will close an energizing circuit for the relay F extending over the left hand inner front contact and armature of D_1 , the left hand inner back contact and armature of RT and the left hand outer front contact and armature of the relay RZ . The relay F becomes energized and locks up to ground at the left hand and outer front contact of armature D_1 . In its right hand and inner armature of the back contact, the relay prevents connection of battery to the line finder brush k and thus to the conductor $Wk3$ over which a second calculator would otherwise become attached, as described in the first case which we have discussed.

50 Normally, as described in the first case, the relay RT of Fig. 2 becomes energized only when the relay D_2 of Fig. 2A energizes. In the present case, since there is no second calculator attached, the energization of the relay of RT must be effected locally and this accomplished over the ground applied through the left hand outer armature and front contact of the relay F . The relay RT of Fig. 2 will now function as in the first case, to apply ground to wire SCW , for the purpose already described.

Breaking of pairs

When all calculating machines are in use, some singly and some in pairs, all the RT relays are operated, and the pair-breaking relay PB_1 releases since it is normally energized over outer right back contacts of one or more RT relays. If now a new call enters, relay PB_2 operates from ground, via PB_1 back contacts, ST left outer front contact; and the marker RM starts to rotate from ground, via PB_3 back contacts, PB_2 left front contacts, SL_2 right back contacts, interrupter contacts of RM to the winding of RM in order to find a calculator which is assisted by 60 a second one. Such a calculator is characterised

by having its relay D1 operated and its relay F non-operated. At the moment brush RM1 of RM reaches the contact representing such a calculator in a contact bank rm, PB3 operates in series with F from ground via right winding of PB3, right front contacts of PB2, brush RM1 and contact of rm, left inner front contact of RT, left inner front contact of D1, winding of F relay to battery. The right winding of PB3 has sufficient resistance so that relay F does not now operate. The operation of PB3 opens the above traced circuit of RM stopping this. PB3 energises the slow relay SL1 over left front contacts of PB3. SL1 energises SL2 over its front contacts. This latter introduces the low resistance winding of PB3, by grounding such winding over SL2 left front contacts in order to operate F. When this operates, it removes the holding potential of the assisting calculator so that this releases and attaches itself to the calling station. The starting circuit is released, and therefore RM, after the release of relays SL1 and SL2 will not move further. If, however, there are still unsatisfied calls, RM will advance to the contact rm of the next paired calculator and will liberate another circuit in the manner explained above.

What we claim is:

1. An electric calculating system comprising a plurality of stations each having means for calling and means for transmitting signals representing a problem, a plurality of remotely controllable electric calculator equipments each adapted to produce signals representing a solution responsive to the reception of said signals representing a problem, switching means for interconnecting any one of said stations variably with one or two random ones of said calculator equipments, a circuit common to all of said calculator equipments, relay means in said circuit operable only when a predetermined number of calculator equipments are in use, means for setting said switching means into operation responsive to the actuation of the calling means of one of said stations, and means variably controlling said switching means so as to cause the connection of one or two of said calculator equipments to said one station under the control of said relay means.

2. An electric calculating system comprising a plurality of stations each having means for calling and means for transmitting signals representing a problem, a plurality of remotely controllable electric calculator equipments each adapted to produce signals representing a solution responsive to the reception of said signals representing a problem, switching means for interconnecting any one of said stations variably with one or two of said calculator equipments, test means comprising a relay responsive to the condition that all the calculating equipments are simultaneously in use, and means controlled by said relay and responsive to an additional call received from another calling station for disconnecting one calculator equipment from a station which has been connected with two calculator equipments while maintaining the other of said two calculator equipments connected thereto.

3. An electric calculating system according to claim 2 wherein said means for disconnecting one calculator equipment comprises means for selecting at random a pair of calculator equipments from all of the pairs of calculator equipments which are connected to the calling station.

4. A calculator system including a central station, a plurality of calculating devices at said

central station, each device having a plurality of transmitting contacts, a plurality of substations each comprising a transmitter, a receiver responsive to signals from the transmitting contacts of a calculating device, a calling circuit for initiating the connection of the associated substation transmitter and receiver with at least one of said calculating devices, a line finding switch individual to each calculating device having a set of contacts connected thereto, a plurality of groups of contacts on each switch, circuits connecting each substation to an individual contact group, other circuits interconnecting corresponding contacts of said groups of the respective switches, means responsive to the operation of the calling circuit at a substation for setting all line finding switches of idle calculating devices in motion, means for arresting a line finding switch and thereby connecting an idle calculating device to the calling substation, and means effective thereafter when more than a predetermined percentage of the calculating devices are idle to maintain the remaining line finding switches of the idle calculating devices in motion, means for arresting the line finding switch of another of the idle calculating devices in position to connect the associated calculating device in parallel with the calculating device first connected to the calling substation, and means for stopping the line switches of the idle calculators after a sub-station has been connected to a pair of calculating devices.

5. A calculating system according to claim 4 in which additional means responsive to the initiation of a call from an additional calling sub-station are provided for disconnecting one of the pair of calculating devices connected to a substation, said last means being effective when more than a predetermined percentage of calculators are in use.

6. A calculating system according to claim 4 in which means are provided for disconnecting one of the pair of calculating devices connected to a substation effective when more than a predetermined percentage of calculators are in use and when an additional call is received from another calling sub-station, said means comprising a relay associated with each calculator device provided with a back contact, means for holding said relay in operated condition while the corresponding calculator is in use, a circuit connecting the back contacts of all of said relays, and a pair-breaking relay held in ineffective position by said circuit so long as any calculating device is not being used.

7. A calculator system according to claim 4, in which said calculating devices are each provided with means for comparing the operation of the transmitting contacts of the respective calculating devices which are connected in parallel to one another, while said parallel connected calculating devices are operating to effect transmission of signals to the sub-station receiver operatively associated with said calculating devices.

8. In a calculator system having a plurality of calculating devices, each of which has a plurality of contacts connected to output circuits for transmission of signals representing successive digits of a calculated result, means for connecting a pair of said calculating devices to a single calculator control means so that each calculating device operates to solve the same problem in the same manner, a plurality of circuits interconnecting corresponding output circuits from the respective said contacts of said pair of calculating de-

vices with each other, a relay adapted to respond to a difference in operation of said contacts of the respective calculating devices and means to operate said relay under control of one or more of said interconnecting circuits.

9. In a calculating system having a plurality of calculating devices of which two are connected in parallel and also connected to a common sender of calculating signals so as to cause identical operation of both said parallel connected calculating devices and parallel solution of the same problem thereby, there being a plurality of output circuits for each calculating device, a plurality of armatures and pairs of cooperating stationary contacts controlled by each of said devices for variably energizing said output circuits for the transmission of signals representing digits of calculations performed by the particular calculating device, means for detecting a difference in the operation of said pair of calculating devices comprising circuits interconnecting the output circuits of the respective calculating devices, relay means associated with each calculator of said pair, each relay means being operatively connected to a corresponding set of said stationary contacts, the arrangement being such that with normal operation of said calculating devices said armatures move in unison between the respective stationary contacts, each device sending out potentials of like sign and both relay means remain de-energized, and with a variation from the normal condition, one or more of said relay means will be energized over one or more of said output interconnecting circuits to indicate a difference in the operation of the devices.

10. In a calculator device, a plurality of prob-

lem data sending and receiving stations, a plurality of normally idle substantially identical calculators, less in number than said stations, switching means controlled by a calling signal from any station for connecting said station to any two idle calculators in parallel, means for sending successive signals representing digits of a computed result to a station simultaneously from both calculators connected therewith, and relay means controlled by said sending means and responsive to a significant difference between the signals sent from the two calculators.

11. In a calculator device, a plurality of problem data sending and receiving stations, a plurality of normally idle substantially identical calculators, less in number than said stations, switching means controlled by a calling signal from any calling station for connecting said station to an idle calculator, or to two idle calculators in parallel, if two are available, means for sending successive signals representing digits of a computed result to a station simultaneously from each calculator connected therewith, and relay means controlled by said sending means and responsive to a significant difference between the signals sent from two calculators connected in parallel.

12. The calculating device according to claim 11, and means for disconnecting from a station one of the two calculators connected therewith and so rendering it idle if no other calculator is idle when another station transmits a calling signal to said switching means.
